UNITED STATES PATENT OFFICE.

EDWIN S. LEINAN, OF FARGO, NORTH DAKOTA.

AGITATOR.

Application filed September 5, 1922. Serial No. 586,234.

To all whom it may concern:

Be it known that I, EDWIN S. LEINAN, a citizen of the United States, residing at Fargo, in the county of Cass and State of North Dakota, have invented certain new and useful Improvements in Agitators, of which the following is a specification.

This invention relates to an improved agitator for culinary use in the beating of eggs, 10 whipping of cream, and like operations.

The primary object of the invention is the provision of an agitator which includes relatively few parts, which are compactly assembled in adjustable relation to most effectively perform the use for which the same is provided.

An important object of this invention is the provision of an agitator including a number of dashers which includes a driving 20 mechanism of adjustable character to compensate for wear upon the different parts thereof.

A further and important object of this invention is the provision of an improved 25 agitator including a plurality of novelly arranged dasher members.

Other objects and advantages of the improved agitator will be apparent during the course of the following detailed description.

30 In the accompanying drawing, forming a part of this specification, and wherein similar reference characters designate corresponding parts throughout the several views,

35 Figure 1 is a front elevation of the improved agitator, showing the cooperating parts thereof.

Figure 2 is a side elevation of the improved agitator, showing several parts 40 thereof in section, in order to disclose the cooperative relation of the agitator details.

Figure 3 is a fragmentary view, partly in section, showing cooperating parts of this invention.

45 Figure 4 is a fragmentary cross sectional view, showing an adjustable view of the agitator operating mechanism.

In the drawing, wherein for the purpose of illustration is shown the preferred embodiment of this invention, the letter A generically indicates the improved agitator, including a support B; outer dasher arrangement C; intermediate dasher arrangement D; inner dasher arrangement E; and 50 operating means F.

The support B preferably includes a flat metallic plate 10 provided with a recess 11 extending upwardly from the lower marginal edge thereof and being provided with a transverse opening 12 adjacent the opposite end thereof, said depression 11 and opening 12 being respectively provided for accommodation of certain elements of the dasher arrangements C and D, which will be more specifically mentioned hereinafter. 60 The upper end of the supporting plate 10 is preferably provided with a looped handle portion 14.

Referring to the dasher arrangement C, the same includes a bevelled pinion 15 having a sleeve portion 16 formed upon one side thereof which is circumferentially grooved for receiving a retaining collar 18, which is clamped as by rivets 19 to the supporting plate 10. In this relation, the pinion 15 is mounted in the recess 11 of the plate 10, bearing within the collar 18, and cooperating with certain parts of the guide mechanism F to be subsequently mentioned. The arrangement C furthermore includes the dasher member 21 which is formed of wire or analogous material having certain spaced arms 22 which are connected at their ends to the pinion 15, and depend in spaced parallel relation to support the loop 23 of rigid 85 formation.

The intermediate dasher D includes a pinion 25, which is provided with a portion 26 extending outwardly therefrom grooved for receiving a bearing collar 27, said bearing collar 27 being secured, as by rivets 28 to the same side of the plate 10 as the collar 18 is connected to, and as is illustrated in Figures 1 and 2 of the drawings. A shaft 30 extends axially from the portion 26 of pinion 25, and depends through the axial passageway 30 formed through the pinion 15; said shaft 30 being provided with the passageway 31 opening from the lower end 95 thereof. The shaft 30 thus extends between the arms 22 of the dasher member 21, and is provided with a ring shaped dasher end 32 upon the lower end thereof which is relatively smaller in diameter than the outer dasher ring 23, so that the ring 32 is in fact, confined within the area of the loop 23.

It is to be noted, that the collar 27 retains the pinion 25 within the upper opening 12. 100 The inner dasher is of novel formation, and includes the plate portion 35 having 105

110

certain apertures 36 therein to permit free passage of the liquid in which the agitator A is operated. The plate 35 is provided with a stem 37 extending outwardly from 5 one end thereof bearing within an aperture 39 in the lower end of the dasher loop 32 and being affixed as by welding at 40 to the lower end of the outer baffle loop or ring 23. The plate 35 is also provided with a stem 41 10 which extends opposite to, and aligns with respect to the stem 37, said stem 41 having an enlarged bearing end 42 thereon, which is journalled within the passageway 31 of the shaft 30, so that the plate 35 is disposed 15 within the area of the intermediate dasher loop 32, as is illustrated in Figure 2 of the drawings.

Referring now to the operating means F, the same includes a stub shaft 45, which 20 extends from the surface 46 of the supporting plate 10, said stub shaft 45 being screw threaded at 47 upon its free end for adjustably receiving a thumb nut 48. A master bevelled gear 50 is provided having 25 a polygonal shaped extension 51 axially at one side thereof, said gear 50 having an opening axially thereof for receiving the stub shaft 45, in order that the same may bear thereon. A crank 52 may be provided 30 over the polygonal portion 51 of the master gear 50 in order to rotate the same upon the shaft 45. As is illustrated in Figure 2 of the drawings, the master gear 50 is so disposed upon the shaft 45 that the teeth there- 35 of are in engagement at opposite points with the pinions 15 and 25. The nut 48 may be so adjusted upon the screw threaded portion 47 of shaft 45 that the master gear 50 may be adjusted longitudinally of the shaft 45 40 for engaging the teeth of said pinions.

In operation, it is apparent that as the operator rotates the master gear 50, the pinions 15 and 25 will be turned in opposite directions for rotation of the dasher loops 45 23 and 32 in opposite directions. Due to the fact that the inner dash member E is fixedly connected to the loop 23 and bears within the intermediate dasher arrangement D, it is obvious that the oval shaped plate 35 will 50 be rotated in the same direction as the outer dasher loop 23. This is a superior arrangement, since thereby an egg, or cream may be beaten in a relatively shorter time, and in a more effective manner than can be done 55 with present types of agitators. It is well known, that agitators embodying the pinion drive arrangement soon become inoperative, due to the wear upon the pinions and drive gear, as to cause slip of the teeth thereof. 60 This invention provides for such wear and for any loose bearings, by making the master gear 50 longitudinally slid able and adjustable upon its bearing shaft 45, so that the same may properly engage the pinions 65 15 and 25 in operating relation.

From the foregoing, it can be seen that an agitator has been provided which while simple in operation is very durably constructed, embodying improved beating facilities, and improved adjustable assembly to compensate for wear upon the parts incident to operation. 70

Various changes in the shape, size and arrangement of parts may be made to the form of agitator herein shown and described 75 without departing from the spirit of this invention or the scope of the claims.

I claim:

1. An agitator comprising a support, an inner plate shaped dasher, an outer loop shaped dasher, an intermediate loop shaped dasher, and operating means for said dashers. 80

2. An agitator, comprising a support, an outer dasher member movably carried by 85 said support, a second dasher member movably carried by said support within said outer dasher member, and a third dasher member fixedly connected to said outer dasher member within said second dasher 90 member for movement with said outer dasher member.

3. An agitator, comprising a support, an outer dasher movably connected to said support, a second dasher member movably connected to said support, an intermediate dasher member fixed to said outer dasher member and bearing within said second dasher member, and operating means for 100 moving said outer and inner dasher members in the same direction, and said second dasher member in an opposite direction.

4. An agitator comprising a support, a dasher arrangement rotatably carried by 105 said support and including a looped shaped beating portion, a second dasher arrangement rotatably carried by said support and including a looped shaped beating portion relatively smaller and operating within the looped shaped end of said first mentioned dasher, and a third dasher arrangement including a pair of oppositely extending stems bearing in the second dasher, so that the third dasher operates within said second dasher looped portion, one of said stems of 110 said third dasher being fixedly connected to the loop of said first mentioned dasher for movement therewith, and means for rotating said first and second mentioned dashers in opposite directions. 115

5. In a device of the class described, the combination of a support, a dasher arrangement rotatably carried by said support and including a looped shaped beating portion, a second dasher arrangement rotatably carried by said support including a shaft provided with a loop shaped beating portion operating within the loop shaped portion of said first mentioned dasher arrangement, said shaft being hollow and opening within 120 125 130

- the loop which is affixed thereto, and a third dasher arrangement including a plate portion and a pair of oppositely extending stems, one of said stems bearing in the extreme end of said second mentioned dasher loop and having the same affixed in rigid relation to the end of the first mentioned dasher loop, the other stem of said first mentioned dasher arrangement being enlarged and bearing within the passageway of the shaft of said second mentioned dasher arrangement, so that the plate portion of said third mentioned dasher arrangement operates within the area of the loop of said second mentioned dasher arrangement.
6. An agitator comprising a supporting plate having openings therein, dasher arrangements movably connected to said support including a pair of bevelled pinions 20 rotatably connected upon one side of said supporting plate to have the teeth portion thereof extending beyond the plane of the opposite side of said supporting plate, a stub shaft having a screw threaded end, extending beyond the side of said supporting plate from which said teeth of the bevelled pinion project, a master gear slidably and rotatably bearing on the stub shaft and having a polygonal shaped portion extending 25 axially therefrom, a crank shaft mounted upon said polygonal portion of the master gear for rotating said master gear upon the stub shaft, and an adjustable thumb nut in screw threaded engagement with said 30 stub shaft whereby the master gear may be adjusted longitudinally of the shaft for engagement with the teeth of said pinions for operating the latter.
7. An agitator comprising a support including a plate provided with openings 40 therein and having a handle extending upwardly therefrom, a dasher arrangement movably mounted upon said support including a pinion rotatably connected upon said plate to extend through one of the openings therein, and a wire dasher member depending therefrom to provide a ring shaped loop upon the lower end thereof, a second dasher arrangement including a bevelled pinion rotatably connected to said support 45 plate to extend thru a second opening thereof, said second dasher arrangement including a hollow shaft extending through the pinion of said first mentioned dasher arrangement and being provided with a 50 loop shaped beater member upon the lower end thereof disposed within the area of the loop of said first mentioned dasher arrangement, a third dasher arrangement bearing within the loop of the second mentioned dasher arrangement and having an end 55 thereof bearing within the passageway of said hollow shaft, and an opposite end rigidly affixed to the loop of said first mentioned dasher arrangement, a stub shaft extending from said supporting plate, a master gear bearing on said stub shaft, and adjustable means for holding said gear into 60 engagement with said pinions for operating said dasher arrangements.

EDWIN S. LEINAN.
